UNITED STATES PATENT OFFICE.

CHARLES B. DAWSON, OF SEATTLE, WASHINGTON.

APPARATUS FOR RAISING SUNKEN VESSELS.

1,262,460.

Specification of Letters Patent.

Patented Apr. 9, 1918.

Application filed March 31, 1917. Serial No. 158,989.

To all whom it may concern:

Be it known that I, CHARLES B. DAWSON, a citizen of the United States, residing at Seattle, in the county of King and State of Washington, have invented certain new and useful Improvements in Apparatus for Raising Sunken Vessels, of which the following is a specification.

This invention relates to apparatus for raising sunken vessels, and its object is the provision of efficient and conveniently operated apparatus of this character which may be employed with a relatively small expenditure of time and labor.

With these ends in view, the invention consists in the novel construction, adaptation and combination of parts as will be herein-after described and claimed.

In the accompanying drawings, Figure 1 is a view in side elevation showing the prow of a sunken vessel and means operated from above the water on a barge for introducing the bight of a hoisting cable beneath the keel of said vessel. Fig. 2 is a horizontal sectional view taken through 2-2 of Fig. 1 with parts broken away. Fig. 3 is a sectional view through 3-3 of Fig. 1. Fig. 4 is a view partly in side elevation and partly in vertical section of the ground cutting wheel and the supporting frame therefor. Fig. 5 is a view similar to Fig. 1 with parts omitted and representing the wheel swung down to release the hoisting cable. Fig. 6 is a view in front elevation of the vessel being suspended by cable from a pair of coupled scows or pontoons. Fig. 7 is a sectional view through 7-7 of Fig. 2. Figs. 8 and 9 are detail sectional views through 8-8 and 9-9 of Fig. 3. Fig. 10 is a plan view of a portion of Fig. 6. Figs. 11 and 12 are sectional views through 11-11 and 12-12 of Fig. 6. Fig. 13 is a view in side elevation illustrating a sunken vessel having its bow engaged by hoisting cables and showing manner of engaging another cable. Fig. 14 is a side elevational view of a vessel being entirely supported on hoisting cables.

Referring now to Fig. 1, numeral 15 designates the bow of a vessel V at the bottom of a body of water and partly buried in a bed 16 of fine sand or silt. 17 represents a barge provided with a well 17¹ through which extends an upright pipe 18 having attached, as by a sling 19, an end of a hoisting line 20 which passes through a crane supported pul-

ley block 21 to a winding drum 22 for raising or lowering the pipe. This pipe comprises a plurality of separable lengths to extend from a closed upper end 18¹ to an open lower end 18². Adjacent to its upper end said pipe is provided with a branch outlet 18³ which is connected by a flexible tube 23 with a power-driven pump 24 upon the barge and provided with a discharge connection 24¹.

Framework 25 rigidly supported upon posts 25¹ secured to the barge structure carries pipe-guiding means comprising a frame 26 (Fig. 2) connected to radially arranged rods 26¹ which are slidable in guides 27 secured to said frame-work. Said frame is yieldingly held in axial alinement with the barge well by springs 28 interposed between the guides 27 and adjustable nuts 26² provided on the respective rods. The frame 26 is of sufficient diameter to permit being lowered or elevated therethrough the pipe and the coupling means for the various lengths thereof, but in order to afford lateral support to the upper end of the pipe I provide within said frame a pair of doors 29 hingedly connected at their outer ends by pins 29¹ (Fig. 7) to the frame and having recesses 29² at their inner ends to accommodate the pipe. When in use, the doors are desirably coupled by bolts 29³ passing through flange elements 29⁴ of the doors.

When a length of pipe is to be inserted or removed, the doors would be swung upwardly into the positions in which they are represented by broken lines 29⁵ in Fig. 7.

30 represents a bar axially movable in boxes 31 attached to the pipe 18 and having at its lower end a disk 30¹ which serves as a bearing upon or in the ground according to the character of the same. The upper end of the bar is screw-threaded for engaging an internally threaded beveled gear wheel 32 which is borne upon a standard 33 provided on a platform 33¹ which is slidably connected to the pipe and adjustably movable thereon by means of a spur pinion 34 provided on the platform operating in a rack 34¹ secured to or formed on the upper length of pipe 18. Any suitable means, such as a dog 34² taking in the rack 34¹, may be utilized for securing said platform at adjusted elevations with respect to the pipe.

The gear wheel 32 serves as a nut with respect to the bar 30 and is actuated by a bevel pinion 32² operated by a crank wheel 32¹.

to regulate the elevation of the disk with respect to the lower end of said pipe.

35 represents a counterweight for the pipe 18, being connected with the latter by means of a collar 35¹ and suspending lines 35² passing over sheaves 35³ (Fig. 2) provided on the framework 25.

36 represents a bracket clamped from one of its ends, as at 36¹, to the pipe 18 near the lower end of the latter and from which the outer end of the plate is supported by a link 36². As shown in Fig. 3 the bracket is provided with a notch 36³ thereby enabling the bracket to straddle the bow of vessel V to prevent any relative lateral movement when subjected to strains from the hereinafter referred-to cable.

Hinged connected to lugs 37 depending from near the outer end of said bracket is a plate 38 having in proximity to its free end a pair of apertured bolts 38¹ which protrude through holes provided in the bracket and from which such free end of the hinged plate is suspended by keys 40 extending through the apertures of the respective bolts 38¹. The plate 38 is formed at its underside with a tubular boss 38² (see Fig. 4) upon which is rotatably mounted a peripherally grooved wheel 41 and upon which it is retained by a nut 42 and washer 42¹ connected to a screw-bolt 42².

The wheel 41 is equipped with a series of circumferentially arranged teeth 41¹ which are directed downwardly, as shown, and serve to dig the ground therebeneath when rotatably driven through the instrumentality of a cable C¹, Fig. 1, looped intermediate its length about the wheel and having its ends pulled alternately by motor boats 44, Fig. 13, but which in the illustration are shown as employed in an operation subsequent to that now being explained.

The leads of the cable C¹ are guided to and from diametrically opposite sides of the wheel 41 by passing through hingedly connected shackles 45 (Fig. 8) extending through holes provided in the bracket 36 and releasably supported therefrom by keys 46.

50 In operation, the wheel 41 is driven through the medium of said cable first in one rotary direction by the boat connected to the proper cable lead moving forward while the other boat moves rearwardly, and 55 then the previously operating boat moves rearwardly while the other boat does its turn of hauling upon the lead, and so on, each of the boats alternately becoming operative and inactive.

60 The wheel 41 is thus influenced to dig by its teeth 41¹ the ground, and mix the excavated material with water so as to be in suitable condition to be drawn up through pipe 18 by the pump 24 and thence discharged through the delivery connection 24¹.

The excavated material, moreover, is prevented from spreading and is directed to the suction end of said pipe by means of a wall 36⁶ depending from the bracket 36, substantially as represented in Figs. 1, 3 and 5.

During such excavating, the reciprocating movements of the cable leads *a* and *b*, see Fig. 1, and more particularly the slack one, *a*, will drag through the ground in advance of the wheel to furrow the same and gradually remove the dirt from beneath the forward end of the vessel V substantially as indicated in Fig. 5. The excavating of the ground by the cable may be facilitated by providing the cable with scraper elements, such as C², Figs. 1 and 5, said elements being detached from the cable before the latter is employed in hoisting operations. When this has been attained, the bight or loop of the cable is withdrawn from the wheel 41 and dragged beneath the vessel by the forward travel of both of the boats 44. To enable the cable to be thus taken from the wheel I provide controlling lines 48 having one end of each connected to an eye-bolt 49 of the bracket 36; then successively through apertures provided in keys 40 and 46 to a pulley 49¹ attached to the bracket, and finally to the barge 17 to be manipulated by the operator.

By simultaneously pulling upwardly upon both of the controlling lines 48, the operator disengages the aforesaid keys, whereupon the shackles each drop into the broken line position 45¹ in Fig. 8 to release the respective lead and the bolts 38¹ are released with a consequent swinging downwardly of the plate 38 and the wheel 41, as shown in Fig. 5, thereby depositing the cable upon the ground.

To facilitate the locating and regulating of the wheel 41, pipe 18 and the various associated under-water parts of the invention so far described and with respect to the vessel V, an attendant may advantageously descend into proximity of the vessel. To such ends I provide a suitable submersible receptacle such as a tank 50, Fig. 1, which is raised or lowered from a winding drum 51 on the barge by means of a hoisting line 52. Such tank is provided with one or more glazed sight apertures such as 53, and an aperture 53¹ provided with a lens through which rays from a strong lamp (not shown) may be directed on the work.

55 54 represent circulating tubes by which fresh air is supplied to the attendant within the tank from an air pump 55. Furthermore, a telephone wire, indicated by 56, connecting an instrument in the tank with one on the barge, is utilized to transmit messages to and fro. to direct the operations upon the barge for governing and actuating the dredging, etc.

60 After the cable C¹ has been brought un-

der the keel at the forward end of the vessel, the barge 17 and the apparatus depending therefrom are removed and the operation of raising the vessel is thereupon undertaken through the agency of apparatus which I will now describe.

For this purpose I provide a number of scows or pontoons P^1, P^2, P^3 , respectively arranged in pairs, those of each such pair being coupled preferably in the manner shown in Fig. 6 by means of a girder 56 having near its ends a saddle 57 which is seated upon a stub shaft 58 carried by a chair 58¹ which, in turn, is seated upon bolsters 59 fixedly secured upon the deck of the respective pontoon. By such devices the latter are free to rock without imparting strains upon the girder.

Said girder is desirably of the "built up" type and may be composed of timber elements 56¹, see Figs. 10, 11 and 12, secured against deflecting by truss rods such as 56². A girder is also formed with slots 56³ to accommodate a cable and the grooved sheaves 60 therefor, and at each side of the latter a girder is reinforced by steel channel bars 56⁴ (Fig. 12) or an equivalent. The axles 60¹ of said sheaves are journaled in bearing boxes 61 secured upon a girder, and serve to support the cable, as C¹ in Fig. 6, whose ends are led under guide sheaves 62 located at approximately the longitudinal axis of the respective pontoon and thence to a winch 63, one for each pontoon, and about which the cable ends are wound for taking up the cable slack and also, when required in situations where there is little or no tidal action, to serve in raising the vessel.

After the cable, as C¹, for example, has been drawn by the boats under the keel of the vessel, as hereinbefore explained, the cable ends are delivered to the pontoons and connected, as stated above, to the winches after passing over and under sheaves 60 and 62, respectively. This cable is drawn by its ends being wound upon the winch drums to raise the forward end of the vessel or with the assistance of a second cable C² with respect to a pair of pontoons P², Fig. 13, so that another cable, as C³, may be engaged below the vessel by means of the motor boats 44 which are utilized to drag the bight of each of the cables, after the first, under the vessel.

In thus applying, say the first two or three cables beneath a vessel, the boats would, if desired or found requisite, act alternately to draw the respective leads back and forth to cut a channel, so to speak, through the dirt or silt to afford room for the respective cables.

After the various cables are successively engaged under the vessel, the ends of the cables are delivered to the respective pontoons and applied to the various winches

which are then actuated to cause the cables to participate in the raising of the vessel.

Where there is a rise and fall of water surface due to tides, the cables need only be drawn taut by the winches at low tide so that when the water surface rises, the buoyancy alone of the pontoons will exercise the necessary vessel-lifting force. When the vessel is thus supported by the pontoons, as in Fig. 14, at high tide the vessel may be carried by towing the pontoons into shallow water, to enable the slack of the cables to be taken in at low tide to have the tidal rise again raise the vessel, and so on.

The invention and the manner of its operation will, it is thought, be understood from the foregoing description.

What I claim, is—

1. In apparatus for raising a sunken vessel, a submarine digging device, a cable, and means for operating said cable to actuate said digging device, said means also serving to cause said cable to be brought into position to be utilized for hoisting the vessel.

2. In apparatus for raising a sunken vessel, a submarine digging device, supporting means therefor, means to engage the aforesaid means to an end of the vessel, and a cable controlled from the water surface for operating said digging device, and means for releasing said device from the cable and causing the latter to be deposited into position to be employed for hoisting the vessel.

3. In apparatus for raising a sunken vessel, submarine excavating mechanism comprising a grooved wheel having peripherally disposed digging teeth, a support for said wheel, a cable engaging in the groove of said wheel, motor boats connected to the ends of said cable to thereby rotate said wheel in opposite directions, selectively, to effect the operation of said digging teeth, and means operable from above the water surface for detaching the cable from the grooved wheel.

4. In apparatus for raising a sunken vessel, a submarine excavating mechanism comprising a grooved wheel having peripherally disposed digging teeth, a support for said wheel, a cable engaging in the groove of said wheel, means operating at the water surface to rotate said wheel in opposite directions, selectively, to effect the operation of said digging teeth, and means controlled from above the water whereby the wheel is influenced to release the cable therefrom.

5. In apparatus for raising a sunken vessel, a submarine digging device, means to operate the same, pump-actuated means for removing material excavated by said digging device, means to detachably engage the digging device to an end of the vessel, a hoisting cable, and means to introduce the cable under the vessel by way of the hole produced by said digging device.

- 4
6. In apparatus for raising a sunken vessel, a submarine excavating mechanism, supporting means therefor regulated from above the water to engage the same to an end of the vessel, a cable, and means operating at the water surface for primarily actuating said excavating mechanism and subsequently serving to engage the cable to the vessel.
- 10 7. In apparatus for raising a sunken vessel, submarine excavating mechanism comprising a peripherally grooved rotary wheel provided with digging devices, a support to which said wheel is rotatably mounted, a pipe, a bracket connected to said pipe, hinge connections between one end of said support and the bracket, means for releasably securing the other end of the support to the bracket, a cable passing about said wheel, means acting through the medium of the cable for driving said wheel periodically in opposite rotary directions, and means for controlling the first-named means whereby

the wheel is affected for casting the cable therefrom.

8. In apparatus for raising a sunken vessel, the combination with a barge and two motor-driven boats, of a pipe depending from said barge and having an open lower end, excavating mechanism including a rotary digging wheel supported by said pipe, means operable from the barge for regulating the elevation of both the pipe and said mechanism, a pump on the barge for removing through said pipe material excavated by said wheel, and a cable passing around said wheel and having its ends connected to the respective boats whereby the alternate forward travel of said boats will drive said wheel in opposite rotary directions.

Signed at Seattle, Washington, this 26th day of March, 1917.

CHARLES B. DAWSON.
